UNITED STATES PATENT OFFICE.

DARRELL F. DYKE, OF CHICAGO, ILLINOIS, ASSIGNOR TO THE SENG COMPANY, OF CHICAGO, ILLINOIS, A CORPORATION OF ILLINOIS.

BED-RAIL FASTENING.

Application filed May 12, 1919. Serial No. 296,284.

To all whom it may concern:

Be it known that I, DARRELL F. DYKE, a citizen of the United States, residing at Chicago, in the county of Cook and State of Illinois, have invented certain new and useful Improvements in Bed-Rail Fastenings, of which the following is a specification.

This invention relates to a fastening for metal bed rails and although designed and intended for use in connection with a wooden bed post, it may also be adapted for use with metal posts as well. The principal object of the invention is to provide a fastener of this kind which operates with a wedging action to secure a bed rail in a receiving box in such a manner that the rails are invertible, reversible and interchangeable.

Another object of the invention is to make the housing of a single sheet metal blank and to form the parts thereof so that the attachment of a cross-rail will assist in strengthening the housing. Other objects will appear hereinafter. The invention consists in the novel construction, combination and arrangement of the parts.

In the accompanying drawing Fig. 1 is a perspective looking at the underside of the bed rail fastener constructed in accordance with the principles of this invention; Fig. 2 illustrates a blank of which the housing is made; Fig. 3 is a sectional view; and Fig. 4 is a section taken on the line 4—4 of Fig. 3.

Referring now more particularly to the drawing, the housing is formed up out of a single blank 1 of sheet metal which is adapted to be attached to a bed post 2 by means of fastening screws 3. The blank comprises flaps 4 in which are perforations 5. When the flaps are bent so that they overlap the perforations 5 register with each other so that the fastening devices 3 may be inserted therethrough and into the supporting post 2. In bending the blank so that the flaps 4 overlap, sides 6 and 7 are formed, and extending from the sides respectively are perforated ears 8 and 9 which are disposed adjacent each other at right angles thereto, as clearly shown in Fig. 1, so that a cross-rail 10 may be attached thereto and the housing thus strengthened.

The blank thus formed up provides a rectangular box or housing open at the outer end and into which a side rail 11 may be in-

serted. In order to secure the rail in place and to sufficiently strengthen the housing, a brace 12 is attached to the top of the housing and to the bottom thereof by extending a reduced portion of the brace through suitable apertures in the top and bottom and by riveting the protruding ends 13 thereof. The reduced section of the brace 12 is extended somewhat inwardly from the riveted ends thereof to form inclined shoulders 14. A U-shaped wedging member 15 fits loosely in the housing and has slots 16 in its ends which adapts it to straddle the reduced ends of brace 12, and the inside of each extremity is formed with a wedging surface 17 which bears against the corresponding inclined shoulder 14 of the brace 12. Extending loosely through the side wall 6 of the housing and threaded into the member 15 is a screw 18 which may have a winged or screw head 19 for drawing the member 15 up tightly against the inclined shoulders 14, forcing the extremities of the member outwardly.

Each web of the side rail 11 is formed with a slot 20 extending from the ends of the rail so that when the end of the rail is inserted within the housing, between the housing and the wedging member 15, the slots 20 in the rail will extend around one end of the brace 12 and around the screw 18. By references to Fig. 4 it will be seen that when one web of the rail 11 is in a horizontal position it will extend around the upper end of the brace 12 as shown in full line, and when the rail is partially inverted so that this web stands in a vertical position, as indicated by the broken outline in this figure, the slot 20 therein will embrace the screw 18. Thus the rail is invertible, and as the opposite ends of the rail are similarly formed, it is reversible, and different rails of the same size are interchangeable.

In order to secure a rail in position after it is inserted in the housing, the screw 18 is turned to draw the wedging member up tightly bringing the wedging surface 17 against the inclined shoulders 14 which causes the extremities to be spread outwardly binding the rail tightly in position. In order to release a rail the screw 18 is simply loosened. With this construction it is obvious that the clamping means is always attached to the housing and there is no danger of the parts becoming separated or

lost. The rectangular box or housing formed of the blank 1 is strengthened not only by the brace 12, but also by the addition of a cross-piece 10 connecting the perforated ears 8 and 9. It will be observed that there is a double wedging action of the member 15, as it is necessary for only one of the extremities to engage one web of the angle bar or rail 11 in order to hold the latter in place in either position.

What I claim is:

- 15 1. In a bed rail fastening, a housing having a rectangular opening, a brace extending between opposite sides of the housing in the opening; a wedging member engaging the brace and movable transversely in the housing, and a side rail insertable in the housing and adapted to be engaged in either one of two positions by the wedging member.
- 20 2. In a bed rail fastening, a housing having a rectangular opening, a brace extending between opposite sides in the housing, a member movable on the brace and engaged thereby for wedging movement, and a rail insertable in the housing and held therein by said member.
- 25 3. In a fastening for angle bar bed rails, a housing attachable to a post and having a rectangular opening, and a U-shaped wedging member transversely movable in the same path in the housing for engaging in the angle of an angle bar in either one of two positions and having means for preventing the removal of the member from the housing.
- 30 4. In an angle bar fastening, a housing having a rectangular opening, a brace connecting opposite sides of the housing and formed with oppositely inclined inner shoulders, a member straddling the brace and having inclined portions engageable with the shoulders, and means to move the member transversely in the housing.
- 35 5. In a bed rail fastening for angle bar rails, a housing formed of a single sheet of material folded to form a rectangular box into which the rail is insertable, a centrally disposed brace connecting opposite sides of the box; and wedging means operating in conjunction with the brace and engaging in the angle of a rail for clamping it in the box in a plurality of different angular positions.
- 40 6. The combination with an angle bar bed rail, of a housing with rectangularly disposed sides, a brace connecting opposite sides of the housing, an angularly bent

wedging member movable transversely in the housing and engageable with said brace for wedging action, and means for moving the member in the housing, the angle bar having end slots in its webs which adapt it to extend around the end of the brace in either one of two reversed positions in the housing, and the wedging member engaging in the angle of the bed rail in either position to hold it in place.

7. The combination with a housing having a rectangular opening, of a cross-piece extending between opposite sides and having inclined shoulders, a U-shaped member straddling the ends of the cross-piece and having raised surfaces to engage the shoulders, a member extending through the side of the housing and threaded into the U-shaped member, an angle bar having end slots in its webs which adapt it to embrace one end of the cross-bar and the member threaded into the U-shaped member in either one of two positions.

8. In a fastening for angular metal bed rails, a housing having a rectangular opening, a single slotted wedging member, means for moving the member transversely in the housing to engage in the angle of a rail in either of two opposite positions, and a fixed support within the housing engaging in the slots of and limiting the wedging member to a transverse movement and preventing its disengagement from the housing.

9. In a fastening for angle bar bed rails, a housing, a wedging member having parallel extremities adjacent the sides of the housing, an operating member extending through another side of the housing and threaded into the wedging member, and means within and attached to the housing forming a brace therefor and cooperating with the wedging member to cause its wedging action and also to prevent displacement thereof.

10. In a fastening for angle bar bed rails, a housing having a rectangular opening, a wedging member fitting loosely therein, a threaded member operable from the outside of the housing for moving the wedging member transversely, and means within the housing and attached thereto for effecting the wedging action of the said member when it is moved transversely to grip an angle bar inserted between the housing and the member in either one of two different angular positions.

DARRELL F. DYKE.
